E. B. JACOBSON

INDUCTION OR IGNITION COIL

Filed April 15, 1922

INVENTOR.
Edward B. Jacobson.
BY Harry M. Brown.
ATTORNEY

UNITED STATES PATENT OFFICE.

EDWARD B. JACOBSON, OF PITTSFIELD, MASSACHUSETTS.

INDUCTION OR IGNITION COIL.

Application filed April 15, 1922. Serial No. 553,230.

To all whom it may concern:

Be it known that I, EDWARD B. JACOBSON, a citizen of the United States of America, residing at Pittsfield, in the county of Berkshire and State of Massachusetts, have invented certain new and useful Improvements in Induction or Ignition Coils, of which the following is a specification.

This invention relates to improvements in induction coils.

An object of the invention is to provide an induction or spark coil for use in connection with the ignition system of a motor vehicle, the current from the secondary winding of which is connected to the usual spark plugs of an internal combustion engine.

A further object is to provide an induction coil in which the current produced in the secondary is of greater amperage than in the coils now in use, whereby a more efficient ignition of a vaporous charge is produced.

A further object is to provide an induction coil in which the magnetic circuit is more nearly a closed one whereby greater efficiency is produced.

A further object is to so construct and arrange the various elements or parts of the coil in order that it may be readily taken apart and reassembled, if necessary, for repair.

Further objects and nature of the invention will appear in the body of the specification and will be particularly pointed out in the appended claims.

Referring to the drawings which form a part of the specification.

Fig. 1 is a plan view of the cover plate for closing the upper end of the casing and showing the primary terminals.

Fig. 2 is a vertical sectional view on the line 2—2 of Fig. 1 showing the cups of molded insulation between which the two coils are located, also the manner of securing the parts together.

Figs. 3 and 4 are a plan and a sectional view respectively of the upper cup of molded insulating material.

Fig. 5 is a top plan and vertical sectional view respectively, of the interiorly threaded sleeve or thimble which is located or embedded within the molded insulation top or cover plate.

Fig. 6 is a detail side elevational and end view respectively of the high tension terminal.

Fig. 7 is a detail end and side elevational

view respectively of the interiorly threaded nut which is connected to the tie rod.

Fig. 8 is a detail top plan and side elevational view respectively of the attaching bottom stud for the securing of the coil.

Fig. 9 is a sectional view of the molded insulating top or cover plate and

Fig. 10 is a detail view of one of the discs of magnetic material.

Referring to the drawings in detail:

1 and 2 designate the primary and secondary windings respectively, 3 the usual core of any suitable construction and material as wires of soft or annealed iron. 4 and 5 are the upper and lower cup members of molded insulating material and between which the primary and secondary coils 1 and 2 are placed, as shown. The ends of these coils fit within the depressions 6 and 7 which are formed by the elongated flanges 8. The margins 9 produce the depressions 10, and, molded with and located within each of the depressions 10 are the perforated tubular portions 11 through which passes the two terminals 12 and 13 of the primary coil 1.

Located within the depression 10 of each of the cup members 4 and 5 are discs 14 of thin magnetizable material having openings 15 to receive the tubular portions 11, and a radially arranged opening or slot 16 which connects at its inner end with the curved seat portion 17 in which is located the tie rod 18. These discs engage or are in direct contact with the opposite ends of the core 3, as shown. A good magnetic contact is therefore produced. 19 designates discs of insulating material which are placed within each of the depressions 10 and on the outermost one of the metallic discs 14 which compose the core heads.

The core 3, primary and secondary coils 1 and 2, cups 4 and 5, discs 14 and 19 are secured together and in place as follows:

The tie rod 18 is threaded as indicated at 100 to receive the interiorly threaded bottom stud 21. The end 21' of this stud engages the lower disc of insulation 19 and forces the metallic discs 14 against the lower end of the core 3 and against the bottom of the recess 10 of the lower cup 5. The opposite or upper end of the rod 18 is also threaded as indicated at 22. On this rod is placed the loose sleeve or washer 23 which rests on the outer surface of the upper fibre disc 19. Engaging the threads 22 is an internally threaded sleeve or nut 24 (see Fig. 7) which is formed

with slots 24' to receive a screw driver. This sleeve is located within a second sleeve 25 (see Fig. 5) which is embedded within the cap or top piece 26 of molded insulating material, as clearly shown in Figs. 2 and 9. The lower edge 24' engages the inclined annular shoulder 27 of the sleeve 25 and when the sleeve or nut 24 is rotated it will firmly clamp or draw the two cup shaped members 4 and 5 together, and will also firmly draw the metallic discs 14, which compose the core head against the ends of the core 3. This operation also firmly connects the cap or top piece 26 to the tie rod 18.

15 The piece 25 is formed with an internally formed thread 25' for attaching the coil to a support. In the cap piece 26 is embedded the two terminals 28 to which the two terminals 29 of the primary coil 1 are connected.

30 are the set screws for connecting the coil 1 to a suitable source of electrical energy.

The parts of the coil are enclosed by 25 means of the fibre casing 30 which is preferably water and oil proof. This casing is attached to the base piece 31 by means of the pins 32. The piece 31 is secured to the tie rod 18 by means of the stud 21 shown in 30 Fig. 8. 32 is a high tension button terminal to which the cable is connected that conveys the ignition current to the usual distributor for the spark plugs. It is shown in detail in Fig. 6. The other high tension terminal 35 is indicated at 33.

An important feature of my invention is in the use of the two cup shaped members 4 and 5, and the core heads which are formed of the metallic discs 14.

40 The cup members are formed with a centrally disposed opening 4' to receive the ends of the core 3, as shown.

What I claim is:

1. In an induction coil, the combination, 45 a core, primary and secondary coils thereon, clamping members therefor, said members being formed with recesses on their inner surfaces to receive the ends of the coils, and tubular projections communicating with the 50 recesses to receive the terminals of the primary winding and other recesses formed and located on the outer ends of the members, metallic members located on the said other recesses for distributing the magnetic flux 55 from the core, a tie rod and means thereon for drawing the clamping members toward each other.

2. A cap or closure for one end of an induction coil comprising a member formed 60 of molded insulating material, terminals formed with flanges which are located in the said material for receiving the ends of the primary coil, a centrally disposed interiorly threaded sleeve formed with flanges 65 and also located in the said material and

having its inner end formed with an opening, a tie-rod having a threaded end and located in the opening of the sleeve, the sleeve having a shoulder thereon, an exteriorly threaded nut engaging the threads of 70 the sleeve and a part engaging the shoulder thereof, the said nut having interiorly located threads for engaging the threads on the rod, whereby when the nut is threaded into the sleeve against the shoulder the tie 75 rod may be tightened.

3. In an induction coil, the combination of a member for clamping the core and the primary and secondary coils of an induction coil, said member having depressions on its 80 opposite faces, the depressions on their inner faces being for directly receiving the ends of said coils, metallic discs located in the depressions on their outer faces and which directly engage the ends of the core, 85 a tie rod, means on the rod engaging the discs for drawing the whole together.

4. An induction coil, comprising a core, primary and secondary coils thereon, of a pair of recessed coil clamping members to 90 receive the ends of the coils, means for drawing the members against the ends of the coils, said members having an opening to receive the ends of the core, magnetizable pieces formed with openings and directly 95 engaging the ends of the core and located on the recessed clamping members, the recessed members having tubular projections which enter openings in the magnetizable pieces. 100

5. An induction coil comprising a core, a primary and a secondary coil arranged about said core, a member composed of insulating material and each formed with a centrally disposed opening into which the 105 ends of the core projects, each member having oppositely disposed recesses, the recesses on one side of each member receiving the ends of the said coils, each member having perforated projections to receive the ends of the primary coil, metallic disk-shaped plates formed with openings to receive the projections of each of said members, and located in the recesses on the outer ends of each of said members, said plates each having a radially arranged opening, and means for clamping the members in place comprising a tie rod which is located in the radially arranged opening. 110

6. An induction coil comprising a core primary and secondary windings thereon, a member at each end of the coils and engaging the same and each formed with recesses, an enclosing casing, a closure piece at each end of the casing, metallic disk-shaped members engaging the ends of the core, pieces of insulation on the outermost one of the metallic disk shaped pieces, a tie bolt connected to the closure pieces, one of the closure pieces having an interiorly threaded part 115 120 125 130

therein and a flange part engaging the piece of insulation at one end of the core, the other or upper closure piece having an interiorly threaded part therein, a nut having 5 threads on its interior and exterior and engaging the threads of the interiorly threaded part in the upper closure piece, a tie rod having threads at each end which is threaded into the threads of the first mentioned closure piece, its other threaded end being en- gaged by the internal threads of said nut, a washer on the rod and engaging the piece of insulation at the upper end of the core, whereby when the nut is tightened the closure pieces will be secured to the casing and the metallic disk-shaped pieces forced against the ends of the core and said members at each end of the coils will be forced towards the ends of the coils. 15

EDWARD B. JACOBSON.
